UNITED STATES PATENT OFFICE.

MARY MORGAN AND CHARLES H. HAMMER, OF LIMA, OHIO.

DEVICE FOR INSERTING PILLOWS IN SLIPS.

Application filed July 20, 1927. Serial No. 207,235.

This invention relates to a device for inserting pillows in slips.

Considerable time is lost in institutions such as hospitals and the like in inserting 5 pillows in slips, each of these operations occupying considerable time. An important object of the present invention is to provide a novel device in which the pillow may be enclosed whereby it readily may be inserted 10 in the pillow slip, the device being releasable from the pillow to permit it to be withdrawn after the pillow is inserted in the slip.

A further object is to provide a light resilient device comprising a pair of members 15 adapted to be clamped against opposite sides of a pillow to permit it readily to be inserted in a pillow slip.

A further object is to provide novel means whereby the resilient frames readily may be 20 released to permit them to be withdrawn from the pillow slip after the pillow is inserted therein.

Other objects and advantages of the invention will become apparent during the course 25 of the following description.

In the drawings we have shown one embodiment of the invention. In this showing,

Figure 1 is a side elevation,

Figure 2 is a section on line 2-2 of Figure 30 1, parts being shown in elevation, and,

Figure 3 is a detail perspective view of the device separated from the pillow and slip.

Referring to the drawings, the numeral 10 designates a pillow adapted to be inserted in 35 a slip 11. The device forming the subject matter of the present invention comprises a pair of frames 12 and 13, as shown in detail in Figure 3, these frames preferably being formed of resilient wire and including longitudinal parallel members 14 and transverse end members 15. The frame 12 is provided at one end with a longitudinal projecting locking member 16 having its central portion turned inwardly as at 17 to form a hook, for 40 a purpose to be described. The frame member 13 also is provided with a longitudinal extension 18 having a transverse bar 19 at its extremity adapted to be arranged beneath the hook 17. The side portions of the pro-

50 jection 18 are adapted to extend between the side portions of the projection 16, as shown in dotted lines in Figure 1.

The opposite end of the frame 12 is provided with an extended portion 20 which is 55 extended laterally at its extremity as at 21,

and is provided with a transverse handle portion 22. The corresponding end of the frame 13 is provided with a loop member 23 which extends around the projection 26 formed on the frame 12. The latter elements 60 are loosely associated with each other to permit the frames to partake of considerable relative movement with respect to each other.

The operation of the device is as follows:

With the parts substantially in the position shown in Figure 3, the pillow is inserted between the frames 12 and 13, these elements being movable an ample distance away from each other to permit the pillow readily to be inserted therebetween. The frames are 70 then flexed at their lower ends and the projection 18 is inserted between the side portions of the projection 16, the transverse bar portion 19 being arranged beneath the hook 17, as shown in Figures 1 and 2. The device, 75 and the pillow arranged therein, then may be inserted into a pillow slip, the shape of the pillow being retained by the frames 12 and 13 to permit the inserting action easily to be performed. After the pillow is 80 inserted in the manner described, the loop 23 may be pulled upwardly with a sudden jerking movement, or the operator may grasp the transverse portion of the loop and the handle 22 together to cause the frames 12 and 13 to move longitudinally with respect to each other. This action releases the bar 85 19 from the hook 17 whereupon the device readily may be withdrawn from the open end of the pillow slip. It will be apparent that 90 the friction of the pillow against the slip will prevent them from sliding with respect to each other while the frames are withdrawn, and consequently the pillow will remain in position in the pillow slip.

It is to be understood that the form of the invention herewith shown and described is to be taken as a preferred example of the same and that various changes in the shape, size and arrangement of parts may be resorted to without departing from the spirit of the invention or the scope of the subjoined claims.

We claim:

1. A device of the character described comprising a frame member having a handle arranged adjacent one end, a second frame member provided with a loop portion at one end loosely engaging said handle, both of said members being provided with extended 105 110

portions on their opposite ends, one of said portions comprising hook means normally engaging said other portion and releasable therefrom upon relative movement of said handle and said loop portion.

2. A device of the character described comprising a pair of frame members, one of said members being provided at one end with a longitudinally extending handle, the

10 other of said members being provided at one end with a laterally extending looped portion loosely surrounding said handle, the opposite ends of each of said members being provided with longitudinal extensions, one of 15 said extensions comprising hook means normally engaging a portion of said other extension and releasable therefrom upon relative movement of said handle and said loop portion.

20 3. A device of the character described comprising a pair of frame members, both of said members having handle portions adjacent one extremity, the handle of one of said members being loosely engaged about the 25 handle of the other of said members, and providing means for swinging the opposite ends of said frame members toward and away from each other to permit the insertion of an object therebetween, and means 30 carried by said opposite ends of said members for securing them together and oper-

able from said handles to release said opposite ends.

4. A device of the character described comprising a pair of resilient frame members adapted to receive an object therebetween and having loosely connected handle portions adjacent one end, and means adapted to connect the opposite ends of said members together and releasable upon relative 40 movement of said handle portions.

5. A device of the character described comprising a pair of resilient frame members each including a plurality of spaced longitudinal bars and having handle portions adjacent one end, the handle of one of said members being loosely engaged about the handle of the other of said members, and providing means for swinging said frame members toward and away from each other 50 and for relative longitudinal movement, a hook carried by the other end of one of said members, and a bar carried by the other end of the other of said members and adapted to engage said hook, said bar being releasable 55 from said hook upon relative movement of said handle portions.

In testimony whereof we affix our signatures.

MARY MORGAN.
CHARLES H. HAMMER.
